[57] CLAIM

The ornamental design for a scale, as shown and described.

DESCRIPTION

FIG. 1 is a front, top perspective view of the scale of the present invention;

FIG. 2 is a front elevational view thereof;

FIG. 3 is a rear elevational view thereof;

FIG. 4 is a right side view thereof, the left side view being a mirror image of FIG. 4;

FIG. 5 is a top view thereof; and,

FIG. 6 is a bottom view thereof.

Applicants disclaims written indicia appearing in FIGS. 1 and 5 as not constituting an integral part of the claimed design.
